UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

MECHANICAL MOVEMENT.

1,289,126.

Specification of Letters Patent. Patented Dec. 31, 1918.

Application filed April 6, 1917. Serial No. 160,098.

To all whom it may concern:

Be it known that I, ALBERT H. DE VOE, a citizen of the United States, residing at Westfield, in the county of Union and State 5 of New Jersey, have invented certain new and useful Improvements in Mechanical Movements, of which the following is a specification, reference being had therein to the accompanying drawings.

10 This invention relates to a mechanical movement particularly adaptable for actuating a take-up for looper-threads on sewing machines.

The invention aims to provide mechanism 15 between a rotary driving shaft and an oscillatory driven shaft having a thread-arm or other stitch-forming element fixed thereto for imparting oscillations to the driven shaft each interrupted by a dwell that may 20 be timed to occur before, at or after the driven shaft changes its direction of motion at one extremity of its oscillation.

The construction broadly comprises a plurality of take-up arms fixed to a shaft having 25 a sliding connection with one end of a lever which is movably fulcrumed intermediate its ends on the arm of a rocker and at its other end embraces an eccentric on a rotary driving shaft parallel with the driven 30 shaft.

The invention also consists in certain details of construction which will appear in the following description of the accompanying drawings, in which Figure 1 is a perspective 35 view and Fig. 2 a side elevation, partly in section, of an embodiment of my invention as applied to a sewing machine, sufficient of the construction being shown to make clear its application. Fig. 3 is an enlarged view 40 of the take-up and eccentric, the arms and center of the eccentric being numbered the same in the relative positions they assume during a complete rotation of the main-shaft. Fig. 4 is a diagram of the movement 45 of the take-up arms in different positions of adjustment. Fig. 5 is a graphic diagram showing how the adjustment enables the dwell to be timed before and after the take-up arms reach the end of their stroke.

50 The invention is shown embodied in a two-thread chain-stitch sewing machine having needles 1 coöperating with thread-carrying loopers 2 disposed at an angle to the line of feed and supported on a carrier 3 which is 55 slidingly and pivotally sleeved on a fulcrum-

shaft 4, an extension 5 of the carrier having a ball-and-socket connection 6 with a strap 7 embracing an inclined crank on the main-shaft 9, substantially as in applicant's pending case Serial No. 113,022, renewed 60 August 3, 1916.

With each of the loopers 2 a take-up arm 10 is differentially moved to control the thread carried by the looper so as to insure the formation of perfect stitches in a manner 65 fully disclosed in said copending application.

This application is directed to protect a mechanism for operating the take-up arms and it will now be described.

The take-up arms 10 are endwise adjustably secured by screws 11 to a shaft 12 supported on bearing blocks 13 and 14. A collar 15 adjustably secured to the shaft 12 on one side of the block 14 and an offset 16 70 suitably secured to the shaft at the other side of the block 14 restrain endwise movement of the shaft 12 and compel each of the take-up arms 10 to oscillate in a plane. A pin 17 is secured in the offset 16 substantially at right angles to the shaft 12 and is slidingly connected by a sleeve 18 having a laterally arranged pin 19 with the end of a lever 20. The lever 20 has an apertured boss 21 receiving the pin 19, the end of 75 which pin is tapped for the screw 22 having a relatively large head that is adapted to rest against an end of the apertured boss 21.

At its other end the lever 20 is fashioned 80 into a strap 23 loosely embracing the eccentric 24 fast on the main-shaft 9. Intermediate its ends the lever is fulcrumed as at 25 to an arm 26 on a pin 27 in the bearing bracket 28, which is tongue-and-grooved as at 29 on the block 14 and adjustably connected in place, slots 30 in the bracket 28 85 through which pass the fastening screws 31 tapped into the block being provided for that purpose.

Shifting the bearing bracket 28 in the direction of the arrow Fig. 2 causes the take-up arms to dwell at increasingly later time as graphically illustrated in Fig. 5. The dwells may be timed to occur before or after the arms arrive at their extreme retracted 90 position. By this adjustment for timing it is possible to suit the take-up for coöperation with loopers in a wide variety of chain-stitch machines.

As applied to a take-up the construction 110

furnishes a means for moving the take-up arms differentially with respect to the loopers. While the invention has been described and illustrated as applied to a take-up for controlling the thread carried by loopers in which it is especially advantageous it is to be understood the invention is not so limited. It is believed the invention broadly consists in the mechanical movement for converting rotary motion into a non-uniform oscillatory motion and that it is useful in other relations where differentially actuated elements coact.

Having thus set forth the nature of the invention, what I claim herein is:

- 15 1. In a mechanical movement, a rotary driving shaft, an eccentric element thereon, a lever operatively connected to said rotary driving shaft, a fulcrum for said lever, said fulcrum being movable about a fixed axis, a driven shaft, a sliding connection between said lever and said driven shaft, said driven shaft being adapted to operate an element of a sewing machine.
- 20 2. In a mechanical movement, a rotary driving shaft, an oscillatory driven shaft, an arm adapted to carry thread, said arm being operatively connected to said oscillatory driven shaft, positive means operated by said rotary driving shaft for imparting reciprocations to said arm interrupted by dwells, said means including a shifting and rocking lever.
- 25 3. In a mechanical movement, a main driving shaft, a driven rock-shaft, means between said shafts for imparting oscillations to said rock-shaft interrupted by dwells from each cycle of operations of said main-shaft, including an eccentric on the main-shaft, a lever actuated thereby, a movable fulcrum for said lever, and a sliding connection between said lever and said driven shaft.
- 30 4. In a mechanical movement, a main

driving shaft, a driven rock-shaft, means between said shafts for imparting interrupted oscillations to said rock-shaft from each cycle of operations of said main-shaft, including an eccentric element on the main driving shaft, a lever, a fulcrum for said lever movable about an adjustably fixed axis and a sliding connection between one end of said lever and said driven shaft.

5. In a mechanical movement, a main driving shaft, a driven rock-shaft, means between said shafts for imparting oscillations to said rock-shaft interrupted by dwells from each cycle of operations of said main-shaft, including an eccentric element, a lever, a movable fulcrum for said lever and a pin-and-socket connection between one end of said lever and said driven shaft.

6. In a mechanical movement, a main driving shaft, a driven rock-shaft, means between said shafts for imparting oscillations to said rock-shaft interrupted by dwells from each cycle of operations of said main-shaft, including an eccentric element, a lever pivoted at one end on said element, a fulcrum for said lever, a sliding connection between the other end of said lever and said driven shaft.

7. In a mechanical movement, a rotary driving shaft, a driven shaft, and positive mechanical connections between said driving and driven shafts for imparting oscillations to said driven shaft interrupted by dwells.

8. In a mechanical movement, a rotary driving shaft, a driven shaft, and positive mechanical connections between said driving and driven shafts for imparting oscillations to said driven shaft interrupted by dwells, said connections including an adjustment for varying the timing of a dwell during each of the oscillations.

In testimony whereof, I have signed my name to this specification:

ALBERT H. DE VOE.
